US00D757064S

(12) **United States Design Patent** (10) **Patent No.:** **US D757,064 S**
Seo et al. (45) **Date of Patent:** **** May 24, 2016**

(54) **DISPLAY SCREEN OR PORTION THEREOF
WITH GRAPHICAL USER INTERFACE**

(71) Applicant: **Samsung Electronics Co., Ltd.**, Suwon-si (KR)

(72) Inventors: **Jangwon Seo**, Seoul (KR); **Yong Hwan Kwon**, Seongnam-si (KR); **Jieun Kim**, Suwon-si (KR); **Jihong Kim**, Seoul (KR); **Hyeryung Kim**, Seongnam-si (KR); **Seran Jeon**, Seoul (KR); **Woo-Seok Hwang**, Seoul (KR)

(73) Assignee: **Samsung Electronics Co., Ltd.**, Suwon-si (KR)

(**) Term: **14 Years**

(21) Appl. No.: **29/475,355**

(22) Filed: **Dec. 3, 2013**

(30) **Foreign Application Priority Data**

Jun. 5, 2013 (KR) 30-2013-0029434

(57) **CLAIM**

The ornamental design for a display screen or portion thereof with graphical user interface, as shown and described.

DESCRIPTION

The sole FIGURE is a front view of a display screen or portion thereof with graphical user interface showing our new design. The broken lines illustrating portions of the display screen or portion thereof with graphical user interface are for environmental purposes only and form no part of the claimed design.

1 Claim, 1 Drawing Sheet
